Attorneys

UNITED STATES PATENT OFFICE.

STACEY A. HAINES, OF CLEVELAND, OHIO, ASSIGNOR TO THE HAINES PRODUCTS COMPANY, OF CLEVELAND, OHIO, A CORPORATION OF OHIO.

DRIPLESS FAUCET.

1,397,251.

Specification of Letters Patent. Patented Nov. 15, 1921.

Application filed December 27, 1920. Serial No. 433,167.

To all whom it may concern:

Be it known that I, STACEY A. HAINES, a citizen of the United States, and resident of Cleveland, in the county of Cuyahoga and State of Ohio, have invented certain new and useful Improvements in Dripless Faucets, of which I hereby declare the following to be a full, clear, and exact description, such as will enable others skilled in the art 10 to which it appertains to make and use the same.

The object of the invention is to provide a practical and efficient form of construction for a non-leaking valve, for the faucet 15 or cock of a draft tube, and which is equally well adapted for drawing hot or cold liquids or gases, or for drawing liquids containing any solid substance as a sediment or grounds, which by remaining upon the valve 20 seat would make it impossible to completely close the valve in the faucet.

To avoid the disadvantages found in the use of a faucet that will not close tightly under all conditions, and from which the 25 liquid is always dripping, I have employed the multiple form of valve and operating means therefor, and the mode of construction and combination and the arrangement of parts, hereinafter described, is shown in 30 the accompanying drawings, and specifically pointed out in the claims.

In the accompanying drawings Figure 1, is a vertical central section of the device, showing the device open. Fig. 2, is a bottom plan thereof. Fig. 3, is a vertical section showing the valve closed.

In these figures, the valve is illustrated in connection with its use in a faucet adapted for drawing a liquid such as coffee, and in 40 which the valve is operated by means of a lever, that is actuated by means of the receptacle or container, such as the mug, or saucer for example when the mug or saucer is passed underneath the spout of the faucet, in the act of drawing the liquid from a reservoir, to place it in a position to be filled therefrom.

In these figures, A, is the outlet opening of a draft tube, from which the liquid is drawn; B, is the tube through which the liquid passes to the valve; C, is the valve chamber, comprising an enlargement of the tube B, closely adjoining the outlet opening A.

In this chamber are positioned a multiple 55 number of horizontal partitions having valve seats D, E, and F, respectively, and having a common vertical axis, and on these seats, a corresponding number of valves are seated, G, H, and I, respectively. 60

These seats and valves are successively smaller as they near the outlet opening A, to permit of their introduction in the casing.

These valves are provided with vertical stems, N, O, and P, respectively, which are 65 guided in corresponding openings W', W and W. The upper opening W', is made in a removable cap or plug W², in the wall of the draft tube.

The openings W, W, are formed in the 70 upper valves themselves.

The triple valve shown in the figures, is raised by means of the lever R, pivoted at J, in the casing beneath the lower valve seat, and arm K, provided with a slot M, in 75 which a link or thrust member L, is pivoted. This member L, passes through a vertical bearing V, in the casing, and engages the lower valve and raises first the lower valve, and as the valve stems in turn 80 engage with the valves above, raises in succession the valves above.

The valves are made independent in their movements to a predetermined amount, by leaving spaces above the stems in the openings W, W, and W', when the valves are 85 closed. The total amount of these spaces will be equal to the total amount that the lower valve must be raised.

When all spaces above the valve stems are 90 closed, the valves move simultaneously, as one unitary structure.

In this device, if grains of sediment such as coffee grounds or other sediment should lodge on any one valve seat and prevent it 95 from completely closing, it would not prevent the other valves from acting independently to close on their seats, or if any two seats should become leaky from wear or from the lodging of sediment thereon, the 100 third valve and seat would still operate to close their opening completely.

Springs Z, Z', and Z², serve to close the valves promptly when released.

For convenience in construction the casing is horizontally divided. A shoulder M' prevents the arm K, from falling too far.

The lever R, is so constructed as to be op-

erated by means of receptacles of different sizes, when they are placed underneath the spout.

For this purpose said lever is provided with two or more pressure points or shoulders shown in these drawings at R' and R² where it will be readily engaged by the receptacle at the point adapted to its size, for example, a mug or saucer, if coffee is the liquid to be dispensed.

The receptacle employed will then move the lever a sufficient distance to open all the valves one after the other.

To prevent injury to the fragile material, the lever R, is provided with a soft bumper strip S, formed of felt or rubber which is preferably inserted in a groove or slot, T, in its engaging face.

To enable each valve to tilt upon its seat independently of the others if a grain of a sediment should lodge upon its seat. Each opening W, and the opening W' are tapered or widened at their lower ends, to permit lateral movement of the stems.

Having described the invention what I claim as new and desire to secure by Letters Patent is:

1. In a non-leaking valve mechanism for a faucet, in combination, a dispensing tube having a delivery opening, a vertical enlargement thereon forming a valve chamber, a multiple number of valve seats in said chamber, arranged therein at different levels, a corresponding number of valves for said seats, said valves provided with valve stems, guide means for the stems of the lower valves in the valves above, and guide means for the upper valve in the wall of said tube, and means engageable by the utensil employed in drawing the fluid from said valve, for raising the lower valve, and thereby, in succession the valves above, one after the other, when all of said valves are raised together above their seats, and automatically acting means for returning said valves to their seats.

2. In a non-leaking valve mechanism, in combination with a draft tube, provided with an outlet opening, said tube enlarged intermediate of its ends to provide a vertical valve chamber, spaced horizontal partitions in said chamber, said partitions provided with aligned valve seats, corresponding valves for said seats, axial valve stems for said valves, the upper valve stem provided with a vertical guide in the wall of said draft tube, and the remaining valve stems each provided with a vertical guide in the next adjacent valve above, each lower valve stem when raised engageable with and operating to raise the valve above, and each lower stem having a predetermined amount of vertical movement before engaging the valve above, and means for raising the lower valve, and thereby in succession raising the other valves.

3. In a dripless valve mechanism in combination, a draft tube, a vertical valve chamber therein, a multiple number of spaced valve seats in said chamber, arranged at different levels, and valves therefor, stems for said valves, the upper valves provided with guide openings, in which the stems of the lower valves are guided, and a separate guide opening in said tube for the stem of the upper valve, said guide openings permitting a predetermined amount of independent movement of each valve above its seat, an arm pivoted in said chamber, means for operatively connecting said arm with said lower valve, and an operating lever for said arm.

4. A composite valve mechanism including in combination therein, a dispensing tube having a delivery opening an enlargement thereon forming a valve chamber, independently movable valve parts seated in said chamber, one part being actuated by the one preceding and in turn actuating the part succeeding, so that the various parts close successively and are open successively but in reverse order, a transversely and pivotally mounted actuating member in said chamber and adjacent to one of the said valve parts, and protruding through the wall of said chamber, means outside of said wall for rocking the said member, and means on said member for actuating one of the valve parts, substantially as described.

5. A valve mechanism including in combination, a dispensing tube having a delivery opening, an enlargement thereon forming a valve chamber, a valve therein, an actuating member in said chamber connected with said valve, said member being pivotally mounted and having portions protruding through the chamber wall, and means outside said wall adapted to be actuated by thrust of the receptacle to be filled from said opening for rocking said member.

6. In an automatic valve mechanism, in combination, a valve chamber having inlet and outlet openings, spaced valve seats in said valve chamber, and independently movable valves seated thereon, said valves and valves seated being of different sizes and arranged in vertical and axial alinement, the seats and valve being successively smaller as they near the outlet opening, the said valves being normally out of operative contact with each other, each valve when raised serving to raise in turn the next larger valve, and means for operating the smaller valve.

7. In a valve mechanism, a valve chamber a multiple number of tapered valve seats vertically spaced apart, therein, a valve resting upon each tapered seat, each valve provided with a vertical stem, the stem of the lower valve having a limited vertical movement in the adjacent valve, and adapted to engage and raise the adjacent valve in turn when said lower valve is raised from its seat,

and manually operated mechanism for raising said lower valve from its seat, said valve chamber provided with a tubular guide opening in its wall in which the stem of the upper 5 valve is movably secured.

8. In a faucet in combination, a draft tube having a horizontal portion and a vertical portion, a valve chamber in said vertical portion, said valve chamber terminating in a 10 discharge nozzle, upper and lower valves in said valve chamber, tapered seats for said valves, each valve provided with a vertical stem extending above the valve, and the lower valve, provided with a vertical stem

extending below said valve, a guide therefor 15 in said chamber below said lower valve, a guide opening for the upper stem of said lower valve in the valve above, and a guide opening for the valve stem of said upper valve in the upper horizontal wall of said 20 draft tube.

In testimony whereof, I hereunto set my hand this 23rd day of December, 1920.

STACEY A. HAINES.

In presence of—

W.M. M. MONROE,
CHAS. F. SIPE.
